UNITED STATES PATENT OFFICE

BRADLEY DEWEY, OF CAMBRIDGE, MASSACHUSETTS, AND THOMAS L. TALIAFERRO, OF CHICAGO, ILLINOIS

DRYING APPARATUS

Application filed January 22, 1926. Serial No. 82,983.

This invention pertains to apparatus for drying plate-like or annular objects, for example can ends, which have been coated or partially coated upon one or both sides with lacquer, sealing compound or other fluid, semi-fluid or plastic substance and which must be kept separate from one another until the coating material has become wholly or partially dry or oxidized, to avoid adhesion, 10 or to permit of unhindered drying or oxidation, or to facilitate vulcanization.

Principal objects of the present invention are to provide apparatus which without adjustment is capable of handling plate-like 15 objects, for example disks or rings, varying through a substantial range of thickness, diametral size or contour; to provide apparatus for drying such objects while the latter are supported upon edge in substantially vertical position and in spaced relation; to provide apparatus of simple type having a minimum number of parts and capable of 20 drying fluids distributed over portions of such plate-like bodies rapidly and uniformly and to which the bodies may be fed automatically if desired by the use of known devices and which will discharge the dried bodies automatically; to provide apparatus which 25 will automatically separate adhering bodies from those which are normally separate and which will eject such adhering bodies from the machine at a point different from that at which the properly separate and dried bodies are delivered; to embody the invention 30 in a unit structure which may be readily multiplied to increase the capacity of the apparatus as a whole without a proportionate increase in the amount of the drying medium supplied; to provide apparatus in which the 35 drying medium, if such be employed, is conserved and used in an economical manner; and to prevent the spreading of oil from 40 bearings of moving parts onto the coated bodies.

45 In the accompanying drawings a preferred embodiment of the invention has been illustrated by way of example together with certain desirable modifications, and in such drawings:

50 Fig. 1 is a side elevation with certain parts

broken away showing the complete apparatus but omitting the feed devices;

Fig. 2 is a fragmentary plan view of the apparatus shown in Fig. 1 but on a larger scale and illustrating a plurality of plate-like circular bodies passing through the apparatus;

Fig. 3 is an elevation showing the delivery end of the machine;

Fig. 4 is a section on the line 4—4 of Fig. 1;

Fig. 5 is a similar section substantially on the line 5—5 of Fig. 1, and showing a portion of a feed device;

Fig. 6 is a fragmentary horizontal section substantially on the line 6—6 of Fig. 5;

Fig. 7 is a fragmentary vertical section on a large scale showing details of construction of a roller bearing forming an element of the apparatus;

Fig. 8 is a section similar to that of Fig. 4 but illustrating a modification in which certain parts disclosed in Fig. 4 are duplicated;

Fig. 9 is a fragmentary plan view;

Fig. 10 is a corresponding fragmentary end elevation illustrating a further modification in which a plurality of parallel conveyors are employed;

Fig. 11 illustrates a further modification, the parts being in vertical section;

Fig. 12 is a fragmentary vertical section, more or less diagrammatic, illustrating a further modification particularly adapted for handling plate-like bodies of a generally rectangular contour;

Fig. 13 is a view similar to Fig. 12 illustrating another modification;

Fig. 14 is a fragmentary side elevation of the drive shaft for the conveyor of the apparatus shown in Figs. 1 and 2;

Fig. 15 is a diagrammatic vertical section illustrating apparatus embodying a combination of the devices shown in Figs. 8, 9 and 10, and

Figs. 16 and 17 are diagrammatic views illustrating further modifications.

In drying plate-like bodies of circular contour, for example can ends of the usual type, apparatus such as disclosed in Figs. 1 to 7 is preferred, since this preferred mechanism

provides for a slow rotation of the circular or disk-like member about its own axis as the drying operation proceeds, such rotation tending to facilitate a uniform distribution 5 of the coating material around the entire circumference of the disk and a uniform access of the drying medium to the material to be dried. However, in dealing with plate-like bodies of non-circular contour, arrangements 10 such as shown in Figs. 12 and 13 are permissible, since, if the coating material be of proper consistency and composition, little if any flow of the coating material occurs during the drying process.

15 Referring now more particularly to the construction illustrated in Figs. 1 to 7, the frame comprises spaced supports, for example the supports 1 and 2, which carry the side frame members 3 and 4 which, as here 20 illustrated, consist of channel bars with their flanges turned outwardly. While such bars are convenient and desirable for the purpose, it is obvious that the side members of the frame may be constructed in other ways 25 without departing from the invention.

The side members 3 and 4 are connected at their opposite ends by members 5 and 6 respectively, which space the side members properly and hold them in assembled 30 relation.

The end member 6 is provided with openings for the reception of journal bearings in which parallel shafts 7, 8 and 9 (Fig. 6) may turn. These shafts project outwardly beyond the member 6 and at its outer end the shaft 7 is furnished with a spur gear 10 and with a bevel gear 11, the latter meshing with a gear 12 mounted on a transverse shaft 12^a turning in bearings 13 and 14 attached to the side members 3 and 4 of the frame. The shaft 12^a carries fast and loose pulleys 15 and 16 respectively, adapted to receive a belt driven 40 from any suitable source of power.

The shafts 8 and 9 are provided respectively with gears 17 and 18, the gear 17 meshing with the gear 10 and also with the gear 18, the arrangement being such that the shafts 7 and 9 turn in the same direction while shaft 8 turns in the opposite direction. The axis 50 of the shaft 8 lies in a horizontal plane above that in which the axes of the shafts 7 and 9 are disposed, as illustrated in Fig. 5.

The shaft 7 extends lengthwise of the drying chamber defined by the side members 3 and 4 of the frame and is journalled at its other end in a suitable bearing in the end member 5. At this end the shaft 7 is furnished with a pinion 19 of the same diameter as the gear 10 which meshes with a gear 20 of the same diameter as the gear 17 and which is mounted upon a short shaft 21 turning in suitable bearings in the end member 5.

The shaft 8 is furnished with a sleeve 8^a (Fig. 14) at its inner end, such sleeve being

splined or otherwise secured to the shaft 8, and this sleeve is furnished with a helical groove 23 in its peripheral surface for the reception of the end of a helical spring conveyor 22. The end of this conveyor 22 is 70 threaded into the groove in the sleeve 8^a and it is then permanently secured to the sleeve by the use of solder, brazing or other suitable means. This helical coil conveyor extends lengthwise of the apparatus parallel 75 to the shafts 7 and 9 and at its opposite end is secured to the shaft 21, the latter preferably having a sleeve similar to the sleeve 8^a to which the spring is attached. If desired, one or both of the sleeves 8^a may be movable 80 axially of its shaft to compensate for the expansion or contraction of the spring conveyor.

The shaft 9 also extends lengthwise of the apparatus but terminates at a point spaced 85 a short distance from the inner face of the end member 5. The shafts 7 and 9 are parallel to each other and as above noted preferably have their axes disposed somewhat below the axis of the shaft 8 and of the coil spring conveyor. Throughout its intermediate portion the conveyor rests upon and is supported by the shafts 7 and 9.

To support the shafts 7 and 9 intermediate their ends, bearings 24 and 25 are arranged 90 at intervals lengthwise of the apparatus. These bearings 24 and 25 are preferably of roller type disposed in pairs and preferably the inner bearing of each pair is below the outer bearing so that the outer bearing constitutes an abutment to prevent the shaft 100 which it supports from springing laterally outward.

The bearings 24 and 25 are conveniently mounted upon brackets 26 supported upon web members 27 connecting the side members 3 and 4 of the frame. These web members with their bearings may be disposed at any desired interval apart to provide the necessary support for the shafts and the conveyor carried thereby.

Referring to Fig. 7, a preferred construction of bearing roll is illustrated in which the roll-supporting shaft 28 is fixedly secured at its opposite ends to lugs 26^a and 26^b, forming parts of the supporting bracket 26. Upon this shaft 28 spaced rings 29 and 30 are secured. Each of these rings forms the inner member of a ball bearing and is peripherally grooved for the reception of balls 110 31. These balls also engage internal grooves in a ring member 32 forming the outer element of the ball bearing. Each ring member 32 is fixedly secured within the tubular roll 33 constituting the shaft bearing. The ends of the tubular roll 33 are 115 preferably crimped in over end closure members 34, the latter having a close running fit on the shaft 28. The interior of the bearing roll may be supplied with lubricant of suit- 120 125 130

able consistency and since the end members have a close running fit with the shaft 28 there is little danger that the lubricating medium will spread outwardly onto the outer surface of the bearing roll and thus be applied to the articles being dried.

The coils of the helical conveyor are spaced apart a suitable distance to permit the ready entry of the disk-like bodies 35 which are to be dried, such bodies standing on edge between adjacent spires of the conveyor and resting with their peripheral edges upon the shafts 7 and 9, or upon one shaft and the inner surface of a spire of the helical conveyor.

The bodies 35 are thus supported in substantially vertical planes and by rotation of the conveyor are caused to move in a direction substantially perpendicular to their planes from one end of the apparatus to the other.

It sometimes happens that two such bodies may accidentally be stuck together when they are fed to the apparatus and that two such adhering bodies may enter between adjacent spires of the conveyor coil. To prevent such adhering bodies from being delivered with the properly separate bodies after the drying operation has been completed, it is preferred to provide the conveyor at one or more points, for example at the point 36 in Fig. 2 with a section in which the adjacent spires are spaced apart a distance substantially equal to the thickness of a single one of the bodies to be dried. If two or more adhering bodies are disposed in the space between adjacent spires of the conveyor, when they reach the closely coiled portion of the conveyor, they will be ejected laterally therefrom, since the gradually approaching coils squeeze the two-ply plate outwardly from between them. To permit such ejected adhering bodies to escape at this point one or more of the side walls 3 or 4 may be furnished with an opening 37 through which the adhering bodies may be delivered.

The separate bodies which are freely receivable between the coils at the point 36 continue along the conveyor until they reach a point near the end member 5. As above stated, the shaft 9 terminates just short of this end member 5 so that when the dried body reaches this point it is no longer supported at one side and drops freely down through the bottom of the apparatus and is received in a suitable box or other container indicated at 38.

The plate-like bodies may be fed to the receiving end of the conveyor by hand if desired, or may be delivered thereto automatically by means of any suitable device, for example as here illustrated the side wall 3 may be provided with a suitable slot for the entry of a guiding chute 39, such chute being of suitable width to accommodate a plate-like body standing on edge and to permit it to

roll or slide down between adjacent spires of the conveyor coil.

While it may not be necessary to provide any specific drying medium other than air at atmospheric temperature we prefer to provide heating means for heating the air within the chamber defined by the side walls 3 and 4. For this purpose one or more lengths of pipe 40, 40^a and 41^a may be arranged between the members 3 and 4 in a plane below the conveyor coil, such pipes being perforated to provide burner jets and being connected with a supply pipe 43^a through which suitable gas or other fuel may be delivered.

To conserve the heat from the burners, it is preferred to provide a cover plate 41 resting upon the upper edges of the side walls 3 and 4 or preferably upon retaining brackets 42 and 43 mounted upon said side walls. This plate may be a simple sheet of suitable material, for example asbestos board or the like, although if desired it may consist of a hollow casing as indicated in Fig. 8, filled with asbestos fiber, magnesium, or the like indicated at 44 in said figure.

As a further means for conserving the heat applied and using it economically, while at the same time saving floor space, it is contemplated that as illustrated in Fig. 8 the side walls 47 and 48 of the apparatus may be of greater vertical depth than as shown in Fig. 8 so as to accommodate between them a plurality of superposed conveyor coils 45 and 46 mounted upon suitable bearing supports 49 and 50. These bearing supports carry shafts or equivalent guide members corresponding to the shafts 7 and 9 above described. In this arrangement the heating jets 51 are disposed below the lowermost of the conveyor coils and the heated air will then rise through the several superposed conveyor units, thus acting successively to dry the covers or other bodies, while they are being moved. In this type of apparatus, or in the previously described type, the channels in the members 47 and 48 may be closed by means of cover elements 52 and 53 respectively, and the space within said channels may be filled as indicated at 54 with asbestos fiber, magnesium, or other suitable heat insulating material.

If the apparatus be arranged as illustrated in Fig. 8 with a plurality of conveyor coils superposed, each conveyor may if desired be of sufficient length to permit the completion of the drying operation while the plate-like bodies are traversing the length of the apparatus thus increasing the capacity of the apparatus without increasing the floor space necessary for a single conveyor. On the other hand if desired the length of the apparatus may be made substantially less than that necessary when a single conveyor is employed and the plate-like bodies after being partially dried while traversing the upper conveyor

path may then be permitted to drop into the next lower conveyor and traversed in the reverse direction while the drying is completed, as illustrated at the lefthand side of Fig. 15.

In Figs. 9 and 10 an alternative arrangement is illustrated for securing a saving in floor space. In this apparatus parallel conveyor coils 55 and 56 are disposed side by side, such coils preferably being of opposite pitch but turning in the same direction. These coils may be provided with supporting guides such as the shafts 7 and 9 above described, or other suitable means such as hereinafter described, for supporting the plate-like members as they are traversed from end to end of the apparatus.

In the arrangement shown in Figs. 9 and 10, it being assumed that the plate-like bodies 20 are first fed to the coil 55, the latter is provided near its delivery end with an ejector pin 60 which connects adjacent spires of the coil. Closely adjacent to the plane of rotation of this pin 60 a transverse guide rail 25 61^a is arranged, such rail being supported by means of a bracket 62^a which may be attached to the end member 5 of the frame. When a plate-like body propelled by the conveyor 55 in the direction of arrow 57 reaches 30 a point such that it is engaged by the pin 60 in the revolution of the latter, it is forced laterally out of the conveyor 55 and while resting against the guide member 61^a is pushed over between the spires of the conveyor coil 56. The latter coil immediately begins to propel it in an opposite direction as indicated by the arrows 58 in Fig. 9, and the dried body may be ejected at the same end of the apparatus at which it was admitted. It will be obvious to those skilled 35 in the art that many other devices might be employed to transfer bodies from one conveyor to a parallel conveyor.

In the apparatus illustrated in Figs. 1 to 45 7 the disk-like body which is to be dried is fed in through the chute 39 between the coils of the conveyor and its edges rest upon the spaced guide shafts 7 and 9. Since these guide shafts are positively driven and turn 50 in the same direction they tend to impart a relatively slow movement to the disk-like body by engagement with its peripheral edges. At the same time the rotation of the spiral conveyor propels the disk-like body 55 lengthwise of the apparatus.

Preferably the proportions of gears 10, 17 and 18 are such that the peripheral speeds of shafts 7 and 9 and helical spring 22 are substantially equal. The rotation of the 60 shafts 7 and 9 substantially eliminates frictional wear between the conveyor coil and such shafts while the slow rotation of the disk-like bodies in traveling along the apparatus effectually prevents the coating material from gathering at one point.

While we prefer to employ the rotating shafts 7 and 9 for supporting the helical conveyor, it is contemplated that under some circumstances these rotating supports may be dispensed with. Such an arrangement is 70 illustrated in Fig. 11, wherein a bearing support 61 of substantially U-shape in section carries anti-friction bearing elements 62 and 63 at the upper ends of its arms. Such elements, for example, may be of bearing bronze, Babbitt metal or any material suitable for the purpose. These bearings 62 and 63 support the helical coil conveyor H which may be of substantially the same type as the coil 22 above described. This coil is connected 75 at one or both ends to suitable driving means by which it is rotated for propelling the plate-like bodies B interposed between its spires. In this instance the plate-like bodies, being subjected to the lateral frictional thrust 80 of the rotating conveyor, tend to move to one side of the conveyor axis. To prevent the bodies while being dried from escaping laterally from the conveyor a guide bar 66 is provided at a point somewhat above the bearing 63, such bar extending lengthwise of the conveyor and engaging the peripheral edge 85 of the disk-like body as the latter moves from one end to the other of the apparatus.

The apparatus is adapted not only for drying disk-like bodies but also bodies of other contour, for example can bodies of rectangular or oval shape. Furthermore it is contemplated that it may not be desirable under 90 some circumstances to have the body, whether of disk-like or other form, engage the rotating shafts 7 and 9 which support the conveyor. As shown in Fig. 12, although a pair of rotating shafts 64 and 65 similar to the shafts 7 and 9 is provided for supporting the conveyor helix 64^a, we provide independent 95 guide members 66^a and 67 for supporting the body 68 to be dried. These guide members 100 66^a and 67 may consist of substantially straight and parallel rods suitably supported 105 in a plane above the upper portions of the shafts 64 and 65 and extending substantially from one end of the apparatus to the other. To prevent lateral movement of the body 68 while being dried we may also furnish guard 110 rails 69 and 70 engageable with the side portions of the body during the travel of the latter.

In Fig. 13 a further modification is illustrated wherein although the shafts 71 and 72 corresponding to the shafts 7 and 9 above described directly support the helical coil 73, and wherein although the plate-like body K to be dried rests directly upon the shafts 71 and 72, we nevertheless provide guard 115 rails 74 and 75 engaging the edges of the body to be dried to prevent any lateral movement of the latter.

In Fig. 15 a further possible modification is illustrated diagrammatically. In this fig- 120 125 130

ure four conveyor coils are provided, such coils being indicated by the numerals 76, 77, 78 and 79 respectively. The devices to be dried are fed to the coil 76 and traversed toward one end of the machine by this coil, are then transferred in the manner shown in Fig. 9 to the coil 77 and traversed in the opposite direction, are then permitted to drop into engagement with the coil 78 and again move in the same direction that they were moved by the coil 76, and then are again transferred to the coil 79 and returned toward the feed end of the machine from which they are delivered.

18 It is clearly evident that by further multiplication of conveyor coils and proper transfer from one to another the desired period of drying may be obtained without unduly increasing the horizontal dimensions of the 20 apparatus, and it is evident that by slight modifications, such for example as those herein illustrated and described, the essential elements of the invention may be adapted for use in drying plate-like bodies of substantially 25 any size or peripheral contour.

As is evident from consideration of Fig. 4 of the drawings, the apparatus may without substantial modification handle plate-like members of a very considerable range of 30 sizes, since, as above described, these bodies are supported merely at two points upon the spaced shafts 7 and 9 and the conveyor coil is merely a propelling element which retains the bodies in upright position as they are 35 moved. It is thus clear that the apparatus, without any adjustment whatever, is capable of handling a large range of sizes of plate-like or annular body so that no time is lost in adjustment in changing from one size to another, and it is unnecessary to employ skilled 40 labor in operating the machine.

While heating means has been illustrated herein as one mode of accelerating the drying operation, it is contemplated that other means 45 may be employed, such for example as by the delivery to said chamber of air from which moisture has previously been removed, or the admission thereto of chemical vapors or other media suitable for drying, oxidizing or 50 vulcanizing the coating material which may be employed.

While the spiral conveyor has herein been shown as an open helical spring coil, it is not essential that this coil be resilient since a coil 55 having rigid spires would be reasonably satisfactory for the purpose, nor is it essential that an open spiral be used since many of the desirable results above described might be secured by the use of a screw conveyor of some 60 other type. Furthermore, as shown in Fig. 17, one or both of the supporting shafts 7^a and 9^a might be provided with a spiral groove 83 of the same pitch as the spiral of the conveyor coil 84. Another modification might 65 employ two or more spiral conveyors 80 and

81 in simultaneous engagement with the plate-like body 82, as illustrated in Fig. 16. It is therefore to be understood that in its broadest aspects the invention is contemplated as including such suggested modifications and rearrangement of the parts as may occur to those skilled in the art, and such as fall within the terms of the appended claims.

We claim:

1. Apparatus of the class described comprising a substantially horizontal screw conveyor for propelling disks to be dried in an axial direction, and an elongate unthreaded support disposed at either side of and below the axis of the conveyor for engagement with the peripheral edge of a disk while the latter is being propelled by the conveyor.

2. Apparatus of the class described comprising a screw conveyor for propelling disks to be dried, a pair of elongate unthreaded rotary supporting members substantially parallel to the axis of the conveyor and adapted to engage the peripheral edge of a disk propelled by the conveyor, and means for concomitantly rotating the conveyor and supporting members.

3. Apparatus of the class described comprising a substantially horizontal screw conveyor for propelling disks to be dried, an unthreaded elongate supporting member at each side of and below the axis of the conveyor, one at least of said supporting members being a rotary roll, said members being adapted to engage the peripheral edge of a disk propelled by the conveyor, and means for rotating the conveyor and said supporting roll or rolls.

4. Apparatus for conveying disk-like bodies comprising a rotating helical spring having its spires spaced to receive between them the disks to be conveyed and to progress said disks bodily in an axial direction while rotating the disks, and an unthreaded rotary guide element at each side of the vertical plane of the axis of the spring, said guide elements being disposed in a horizontal plane above the plane tangent to the lowest point of the periphery of the spring.

5. Apparatus of the class described having means for propelling disk-like bodies axially in a predetermined path and for rotating them as they progress along said path, said means comprising a single rotating screw conveyor and an unthreaded rotating support engageable with the edge of the moving disk, said support being at a fixed and unvariable distance from the axis of the conveyor, the conveyor and support being so constituted and related as to permit them to handle disks of a substantial range of sizes.

6. Apparatus of the class described comprising spaced elongate supports substantially parallel to one another and in substantially the same horizontal plane, said supports being adapted to engage the peripheral

edges of plate-like bodies of different sizes and thereby to support said bodies, and a helical spring conveyor having its axis disposed between said supports in a plane above the plane of said supports, said conveyor being adapted to receive bodies of any of said sizes between its spires and to push them along said supports.

7. Apparatus of the class described comprising a frame, an elongate helical spring conveyor extending longitudinally of the frame, spaced parallel rotary shafts extending lengthwise of the conveyor and supporting the latter between them, and means for 15 rotating the conveyor.

8. Apparatus for conveying plate-like bodies comprising a rotary helical spring having its spires spaced to receive between them the bodies to be conveyed and to progress said bodies in a substantially axial direction, spaced unthreaded elongate rotary bearings disposed respectively at either side of the spring supporting the latter between them, and means for rotating the spring.

25 9. Apparatus for conveying disk-like bodies comprising a rotary helical spring having its spires spaced to receive between them the disks to be conveyed and to progress said disks bodily in an axial direction, a 30 power driven rotating shaft disposed at either side of the axis of the spring, the spring resting upon the shafts, and means for turning the spring.

10. Apparatus for conveying disk-like bodies comprising a rotary helical spring having its spires spaced to receive between them the disks to be conveyed and to progress said disks bodily in an axial direction, and an unthreaded rotary shaft disposed at either 35 side of the axis of the spring, said shafts constituting supports for the spring, and means for turning the shafts.

11. Apparatus of the class described comprising a single rotary screw conveyor for bodily propelling plates to be dried, a plurality of substantially smooth supporting surfaces extending substantially parallel to the axis of the conveyor and supporting the latter, said surfaces also engaging with the 45 peripheral edge of a plate-like body while being propelled by the conveyor, and means for rotating the conveyor.

12. Apparatus for conveying disk-like bodies comprising a rotating helical spring 55 having its spires spaced to receive between them the disks to be conveyed and to progress said disks bodily in a substantially axial direction, a rotating shaft disposed at either side of the spring, said shafts constituting 60 supports for the spring, and means for turning the shafts and spring, both of said shafts turning in the same direction and the spring in the opposite direction.

13. Apparatus of the class described comprising an elongate helical spring conveyor

having its spires spaced to receive between them disks to be conveyed, means connected to one end of the conveyor for turning it, a rotary shaft disposed at either side of and below the axis of the conveyor for supporting the latter, said shafts being substantially parallel to the conveyor axis, and supporting bearings for the shafts, each bearing comprising at least one anti-friction element disposed at either side of the vertical axis of the respective shaft.

14. Apparatus of the class described comprising a substantially horizontal elongate conveyor helix having its spires spaced to receive between them disks to be conveyed, means for rotating the conveyor, a pair of spaced parallel shafts supporting the conveyor between them, and supporting bearings for the shafts intermediate their ends, each bearing comprising a pair of anti-friction rolls disposed at each side of the vertical axis of the plane of the respective shaft, the plane of the axes of each pair of anti-friction rolls inclining downwardly toward the vertical plane of the conveyor axis.

90 15. Apparatus of the class described comprising an elongate rotary helix having its spires spaced to receive between them disk-like bodies to be propelled, a pair of rotary shafts parallel to and supporting the helix between them, and bearings supporting the shafts at spaced points, said bearings comprising pairs of permanently sealed hollow rolls each containing a lubricating medium.

100 16. Apparatus of the class described comprising a shaft, a journal bearing therefor, means for driving the shaft, a sleeve secured to one end of the shaft, said sleeve having a helical groove in its peripheral surface, a helical conveyor spring having one end portion seated in the groove in said sleeve, and means for rotatably supporting the conveyor spring at a point spaced from said sleeve.

105 17. Apparatus of the class described comprising a substantially horizontal elongate conveyor helix having its spires spaced to receive between them disks to be conveyed, a rotary shaft secured to each end of the conveyor, and means for positively and synchronously rotating said shafts.

110 18. Apparatus of the class described comprising a substantially horizontal screw conveyor for propelling disks to be conveyed, an elongate rotary guide substantially parallel to the axis of the conveyor disposed at either side of the vertical plane of the conveyor axis and engageable with the peripheral edge of a disk propelled by the conveyor, means for turning the conveyor in one direction, and means for turning both guide rolls in the opposite direction.

115 19. Apparatus of the class described comprising a substantially horizontal elongate conveyor helix having its spires spaced to receive between them disks to be conveyed, a

5 rotary shaft secured to each end of the conveyor, a rotary elongate unthreaded supporting shaft substantially parallel to the conveyor, gearing connecting the opposite ends of said supporting shaft to the respective conveyor shafts, and means for driving the supporting shaft.

20. Apparatus of the class described comprising a pair of helical coil conveyors of opposite pitch, means for turning said conveyors in the same direction, means for delivering plate-like bodies to one of said conveyors to be propelled by the latter, and means associated with said latter conveyor for delivering such plate-like bodies to the other conveyor.

21. Apparatus of the class described comprising a pair of screw conveyors, means for rotating said conveyors relatively to one another in such direction that their propelling action is in opposite directions, means for delivering plate-like bodies to one of said conveyors to be moved by the latter, and means associated with the delivery end of said conveyor for delivering such plate-like bodies to the other of said conveyors.

22. Apparatus of the class described comprising a pair of helical coil conveyors, said conveyors being substantially parallel and spaced from one another, a support associated with each conveyor for engagement with the peripheral edge of a plate-like body disposed between adjacent spires of the conveyor, and a stop member adjacent to the delivery end 35 of one conveyor for terminating movement of a body by the latter conveyor and for transferring it to the other conveyor.

23. Apparatus of the class described comprising a pair of helical coil conveyors, said 40 conveyors being substantially parallel and spaced from one another, a support associated with each conveyor for engagement with the peripheral edge of a plate-like body disposed between adjacent spires of the conveyor, 45 means for delivering a plate-like body to one of said conveyors at a point near one end thereof, a transfer pin connecting two adjacent spires of said conveyor at a point near its other end, and a guide extending transversely 50 from one conveyor to the other near the plane of movement of said pin for directing said plate-like body when laterally ejected from the first conveyor by the action of said pin into engagement with the other conveyor.
